Primary Examiner — Martie K Holtje*(74) Attorney, Agent, or Firm* — Wilson Sonsini Goodrich & Rosati**CLAIM**

The ornamental design for a parking meter, as shown and described.

DESCRIPTION

FIG. 1 is a perspective view of a parking meter, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The structural features depicted by broken lines have been shown for the purpose of illustrating portions of the parking meter that form no part of the claimed design.

1 Claim, 6 Drawing Sheets**US D755,650 S**
